POWER ACTUATED PUNCH

Julian W. McManus, 3733 Delmas Terrace,
Los Angeles, Calif. 90034

Filed June 8, 1966, Ser. No. 2,599

Term of patent 3½ years

(Cl. D54—10)

FIG. 1.

FIG. 2.

FIG. 3.

FIG. 4.

FIG. 5.

FIGURE 1 is a side perspective view of a power actuated punch embodying my new design;

FIGURE 2 is a side elevational view thereof of the side not visible in FIGURE 1;

FIGURE 3 is a bottom view thereof;

FIGURE 4 is a view thereof; and

FIGURE 5 is an end view thereof looking towards the handle end of the punch.

I claim:

The ornamental design for a power actuated punch, substantially as shown.
